UNITED STATES PATENT OFFICE.

MICHELANGELO SACCHI, OF TURIN, ITALY.

SPARKING PLUG.

Application filed July 30, 1924. Serial No. 729,175.

To all whom it may concern:

Be it known that I, MICHELANGELO SACCHI, a citizen of the Kingdom of Italy, residing at Turin, Italy, 38 Corso Valentino, have 5 invented certain new and useful Improvements in Sparking Plugs, of which the following is a full, clear, and exact specification.

10 My invention relates to ignition devices for internal combustion engines and has for its object to provide improvements in the known sparking plugs in order to make them more inexpensive in use and useful in operation.

15 The known sparking plugs generally consist of a partially threaded metallic body which is screwed in the engine wall, said body fixedly enclosing an insulating member which usually surrounds or is fitted with 20 a central metallic rod acting as the main electrode of the sparking plug.

25 When sparking plugs are damaged by their insulating member being broken or split, unless they can be repaired there occurs a very considerable waste of material.

30 My present invention provides for the total conservation of the metallic external body of the sparking plug, which practically does never be damaged, even by usual 35 plugs, and of the central metallic rod, with its terminal binding screw, and allows a portion only of the insulating member, with one or more electrode-spikes connected thereto, to be changed by very easy operations of screwing and unscrewing.

35 Said interchangeable members, as a whole, will be termed henceforth the interchangeable ignition plug.

40 Another object of my invention is to provide a sparking plug which will particularly be adapted to high speed engines, where very considerable degrees of pressure and high temperatures are reached.

45 It is known that for these purposes the 50 sparking plugs are required to be well tight, and to have a very efficiently cooled central electrode and porcelains which will not split due to the different action of heat and different expansion coefficients of metallic and insulating portions.

For these purposes, the sparking plug according to my invention is provided with an insulating member which is adapted to be fitted within the metallic bush in the

ignition plug through the end thereof projecting into the combustion chamber in the engine, so that the pressure therein will push the insulating member against its seat in the ignition plug, and assist thereby in assuring tightness. Further, I provide the 55 central portion of the main external metallic body of the plug with openings in its wall, and I considerably reduce in thickness the size of the insulating porcelain so that the latter will absorb a very little 60 amount of heat and transmit same outwardly through its relatively large surface.

The said advantages will be set forth by the following description, reference being had to the annexed drawing forming part 70 of this specification.

In the drawing is shown in axial sectional view a preferred embodiment of my present invention.

The sparking plug according to my invention 75 consists of a substantially cylindrical metallic body 1, with an hexagonal, or like, expansion 2 and an externally threaded portion 3 which is adapted to be screwed, as usual, in the thickness of the engine wall. 80

A chamber 4 is provided in the body 1, and openings 15 are formed in the wall of said chamber. The upper edge of the portion 2 is internally threaded to receive a collar-shaped nut 6 adapted to secure the 85 externally conical insulating member 8 of the sparking plug against the circular seat 7 in the portion 2, the space 71 between said seat and the circular shoulder 81 in the insulating member being preferably fitted 90 with a soft packing piece.

The insulating member 8 has formed there- 95 in a relatively large cylindrical passage 82 in its upper portion, which projects from the metallic body of the sparking plug, while a larger chamber 83 is provided in the lower portion of said member 8, corresponding to the cylindrical body 1 of the sparking plug.

The lower portion 3 of the sparking plug is also internally threaded, and the interchangeable electrode carrying member is 100 screwed from downwardly therein.

The electrode carrying member consists of a hollow cylindrical metallic member 16, adapted to be screwed into the portion 3 of 105 the sparking plug. Said hollow member 16 is provided at its outer edge with one or more projecting electrodes 17 bent towards

its centre, and with a flange 23 at its inner end. The main electrode 9 extends through the insulating member 8, and projects at the upper end of the latter. The said electrode 5 has its lower end 18 opposite the spike or spikes 17, and is enlarged as at 19. The electrode 9 is threaded as shown, and its lower portion is tightly surrounded by an insulating bush 20, which is formed with an 10 inner contraction to provide a seat for the upper shoulder of the enlargement 19, and an outer contraction 21 adapted to bear against the lower face of the flange 23 in the member 16. The upper portion of the 15 insulating bush 20 is surrounded and covered at its upper end by a barrel-shaped insulating piece 22, the lower edge of which is adapted to bear against the upper face of the said flange 23.

20 A nut 24 and a lock nut 25 are screwed against the upper face of the barrel 22 to tighten both said barrel and insulating piece 20 against the flange 23, due to the tension produced by screwing upon the electrode 9.

25 The barrel 22 and nuts 24 and 25 are thus freely surrounded by air entering through the openings 15 and circulating in the chamber 83, so that heat conducted by the electrode 9 will diffuse through said air, while the 30 next upper portion of the said electrode is surrounded by air in the passage 82 and cooled thereby. A washer 10 provided with cross openings 11 allows of the cooling air circulating around the rod 9 and nuts 24, 35 25, thus facilitating the cooling of these parts.

40 A lock nut 12 is used to secure again the upper portion of the central rod against the stationary members of the sparking plug, while a washer 13 and a knurled binding

screw 14 are provided to attach the electric wire thereto.

It will be seen that the several inner portions are thereby efficiently cooled, that the portion of insulating material projecting 45 into the combustion chamber in the engine is so reduced in size as to become considerably less susceptible of being injured because of the variations of temperature therein than by usual sparking plugs, that the 50 tightness is improved due to the tendency of the internal explosion pressure to apply the central electrode and insulating bush thereof against their seats. Above all, however, there is obtained the main advantage 55 of reducing to a minimum the portion to be changed when the sparking plug becomes damaged, owing to that in such cases the interchangeable ignition plug only has to be 60 changed.

What I claim as my invention is:

A sparking plug of the kind described, comprising a cylindrical hollow body having an internally threaded projection, a metallic bush screwed into said projection, a flange 65 at the innermost end of said bush, a contracted insulating member fitted in said bush against the lower face of the flange therein, a cylindrical hollow portion of said insulating member projecting over said flange, a 70 barrel-like insulating member surrounding said cylindrical hollow portion, means being provided to secure together both the internal insulating member and the free edge of the barrel member against the flange in the metallic bush.

In witness whereof, I have hereunto signed my name.

MICHELANGELO SACCHI.
